TIMER-DISTRIBUTER MECHANISM.

1,311,893.

Specification of Letters Patent. Patented Aug. 5, 1919.

Application filed November 19, 1917. Serial No. 202,712.

To all whom it may concern:

Be it known that I, EDWARD R. HODGES, a citizen of the United States, residing at Irvington, in the county of Essex and State 5 of New Jersey, have invented certain new and useful Improvements in Timer-Distributer Mechanism, of which the following is a specification.

In the use of timer distributers for battery 10 ignition systems some means should be provided for the adjustment of the contact operating device, whereby when the timer distributer is installed on the engine with which it is to operate, the proper timing of 15 the contact with respect to the travel of the engine piston may be readily obtained.

In the past it has been customary to use 20 a split shaft or a supplemental shaft end attached to the main shaft and to fasten the cam which operates the movable contact member thereto by means of a taper screw which spreads the split portion of the shaft or supplemental shaft so that it grips the side surfaces of the hole in the cam which is 25 placed upon the split end of the shaft.

Another method that has been used to 30 some extent is to provide a taper on the end of the operating shaft and co-operating taper hole in the cam, drawing the cam down on to the tapered shaft by means of a nut or screw. During the final tightening of the nut or 35 screw the cam is very apt to be turned out of its proper position thus throwing out the timer, all of which is well understood by one skilled in these matters.

Still another method which has been proposed is that of cutting teeth or making indentations in the end of the driving shaft and in the end of the cam and using a screw 40 for holding the parts from relative longitudinal movement and utilizing the teeth or indentations to prevent rotary motion.

It is the object of my invention to provide 45 a mechanism which may be readily and accurately adjusted for the purpose of timing and which may be readily locked in position without any danger, during the locking process, of throwing the cam out of its proper adjusted position.

Another object of my invention is to provide 50 a mechanism which is simpler in construction and hence cheaper to manufacture than any of the devices heretofore used, of which I am aware.

These and other objects will be apparent

after a study of the specification and drawings, wherein Figure 1 is a sectional elevation of a timer distributor with certain parts broken away to show features herein set forth.

60

Fig. 2 is a top plan view of the timer member without the distributor.

Fig. 3 is an enlarged view of the operating shaft with a portion of it in section.

Fig. 4 is an enlarged perspective view of 65 the contact and distributing operating devices.

Fig. 5 is a view of part of the adjusting and locking means.

Referring now to the details in which like 70 numbers refer to corresponding parts in the different views, 1 is a timer plate upon which is mounted a movable contact member 2 carrying contact 3 which is adapted to coöperate with a stationary adjustable contact 4 75 that is carried by an insulated block 5 fastened to the plate 1. 6 is a condenser which is adapted to be connected across the breaker points 3 and 4 in the usual manner. 7 is a bearing member supporting shaft 8 80 which has an annular groove 9 near its end to receive a thrust collar 10, which in Fig. 1 is broken away so as to show the groove 9. The end of the shaft 8 terminates in a spindle 11 having internal threads 12. The 85 end of the spindle 11 is counterbored at 13 to make room for the head of the screw 19 which has a taper 20, the functions of which will be hereinafter referred to. The wall of the spindle 11 has preferably a plurality of 90 holes 14 made therein. The holes 14 are adapted to support gripping members which are shown in the form of balls 18. The cam 15 has hole 17 passing therethrough and terminates in a thimble 16, the outer portion 95 of which carries a slot 21 cut across its end, preferably off center, to receive a distributing finger 22 that distributes the high tension current to the contacts 23 of distributor block 24 in the usual and well understood 100 manner.

As shown in Fig. 1 the cam 15, having a hole 17, is adapted to slide over the spindle 11 and the screw 19 is then turned downward after the cam 15 has been set to its 105 proper location, until the tapered portion 20 engages the gripping members 18 forcing them outward against the interior portion of the cam 15, it being understood that the gripping members 18 are larger in diameter 110.

than the thickness of the wall of the spindle 11 so that the taper 20 can force them outward as and for the purpose described. The engagement of the taper portion 20 with the 5 gripping members 18 tends to lock the screw 19 in position but other well known locking means may be used to prevent the screw 19 from turning after it has been set securely in position. It will now be understood that for 10 the purpose of adjustment, screw 19 is merely turned backward sufficiently to allow the gripping members 18 to let go of the cam 15 which may then be turned to the required position and the screw turned down again 15 to locking position.

I have found this device to be much more efficient than other devices now in the market for the purpose, and I, therefore, desire to be limited in my invention only by the 20 scope of the appended claims.

Having thus described my invention, what I claim is:—

1. In an ignition timer, the combination of a driving shaft, a cam carried by said 25 shaft, a contact member operated by said cam, means for adjusting and locking in position said cam on said shaft consisting of balls supported by said shaft with means for spreading said balls outward into engagement with said cam.

2. In an ignition timer, the combination of a driving shaft, a cam carried by said shaft, a contact member operated by said cam, means for adjusting and locking in 35 position said cam on said shaft consisting of balls supported by said shaft and a screw having a tapered end adapted to pass through said cam and screw into the end of said shaft whereby said tapered end spreads 40 said balls outward to engage said cam.

3. In an ignition timer, the combination of an operating shaft, a hollow cam carried on said shaft, a contact member operated by said cam, gripping members loosely supported in the side wall of said shaft within the hollow part of said cam, and means engaging the shaft for forcing said gripping members into engagement with the interior part of said cam.

50 4. In an ignition timer, the combination of an operating shaft having an interiorly threaded end and a thrust collar groove near said end, a thrust collar to fit said groove, a hollow cam carried on the end of said shaft, a contact member operated by said cam, gripping members supported in the side walls of said shaft within the hollow part of said cam and a screw having a 55 tapered end adapted to screw into the end

of the shaft for forcing said gripping members through the side wall of the shaft into engagement with the interior part of said cam.

5. In an ignition timer, the combination of an operating shaft terminating in an internally threaded spindle, said spindle having a plurality of holes therethrough with gripping members seated therein, a contact operating member consisting of a hollow cam having a thimble projecting therefrom, 65 said cam and thimble being adapted to be carried on said shaft spindle, and a screw having a tapered point engaging the threads in said spindle for spreading said gripping members outwardly through said holes into 70 engagement with said cam.

6. In an ignition timer distributor, the combination of an operating shaft terminating in an internally threaded spindle, said spindle having a plurality of holes therethrough with gripping members seated therein, a contact operating member consisting of a hollow cam having a thimble projecting therefrom, 80 said cam and thimble being adapted to be carried on said shaft spindle, and a screw having a tapered point engaging the threads in said spindle for spreading said gripping members outwardly through said holes into 85 engagement with said cam, and a distributing finger carried by said thimble.

7. In an ignition timer distributor, the combination of an operating shaft terminating in a hollow spindle, gripping means supported by the spindle and extending through its wall into the hollow portion thereof, a contact operating member consisting of a hollow cam terminating in a slotted thimble, said cam and thimble being adapted to fit over said spindle, means 95 engaging said spindle for forcing said gripping means outward into engagement with the interior wall of said cam, and a distributing finger carried by said thimble and having a part to engage the slot in the 100 thimble for the purpose described.

8. In an ignition timer, the combination of an operating shaft terminating in a hollow spindle and having gripping members supported by the spindle wall and extending therethrough into the hollow portion, a hollow contact operating member adapted to fit over said spindle and means for forcing said gripping members into engagement 110 with the interior part of said contact operating member for the purpose described.

EDWARD R. HODGES
